(57) **CLAIM**

The ornamental design for an exercise apparatus, as shown and described.

DESCRIPTION

FIG. 1 is a perspective front view of an exercise apparatus; FIG. 2 is another perspective front view in an extended form thereof;

FIG. 3 is another perspective front view in an extended form thereof;

FIG. 4 shows a front view thereof;

FIG. 5 shows a rear view thereof;

FIG. 6 shows a right-side view thereof;

FIG. 7 shows a left-side view thereof;

FIG. 8 shows a top view thereof;

FIG. 9 shows a bottom view thereof; and,

FIG. 10 shows a rear view thereof in environmental conditions.

The broken lines of the figures showing additional portions of the exercise apparatus are included for the purpose of illustrating environmental structure and form no part of the claimed design.
